(57) **CLAIM**

The ornamental design for a shoe accessory for attachment to shoe laces or cup lid, as shown.

DESCRIPTION

FIG. 1 is a perspective view of an accessory for attachment to shoe laces or cup lid showing my new design, the shoe shown in broken lines for illustrative purposes only;

FIG. 2 is an enlarged perspective view thereof;

FIG. 3 is a front elevational view of FIG. 2;

FIG. 4 is a rear elevational view of FIG. 2;

FIG. 5 is a left side elevational view of FIG. 2, the right side being identical;

FIG. 6 is a top plan view of FIG. 2, the bottom being identical;

FIG. 7 is a perspective view of FIG. 1, the cup shown in broken lines for illustrative purposes only;

FIG. 8 is an enlarged perspective view thereof;

FIG. 9 is a front elevational view of FIG. 8;

FIG. 10 is a rear elevational view of FIG. 8;

FIG. 11 is a left side elevational view of FIG. 8, the right side being identical; and,

FIG. 12 is a top plan view of FIG. 8, the bottom being identical.
